United States Patent Office.

FRANK MILLER, OF INDIANOLA, ILLINOIS.

Letters Patent No. 77,637, dated May 5, 1868.

IMPROVED BOLT-CUTTER.

The Schedule referred to in these Letters Patent and making part of the same.

TO WHOM IT MAY CONCERN:

Be it known that I, FRANK MILLER, of Indianola, in the county of Vermillion, and State of Illinois, have made certain new and useful Improvements in Bolt and Rivet-Cutting Machine; and I hereby declare the following to be a full and exact description of the same, reference being had to the drawings that accompany and form a part of these specifications.

The object of my invention is to provide an instrument for cutting off bolts, rivets, nails, &c., simple in structure, and one easily and expeditiously operated.

Figure 1, perspective view of my device.

Figure 2, view, showing manner of operating.

Figure 3, sectional view of different parts.

Letter A, stationary handle, and one of the cutters.

Letter B, sliding cutter, the counterpart of A.

Letter C, lever, operating an eccentric by which the cutter B is moved.

The drawings will sufficiently show the manner of constructing my machine. The parts A and B are made of wrought iron, provided with steel jaws or cutters, *e. e.*, properly tempered for that purpose.

It will be observed that these cutters are flat on the under side or surface, so that they will cut perfectly smooth and even at the point required.

The parts A and B are connected by bolts *ff*.

In the sliding cutter B are slots, *h h*, through which the bolts *ff* pass. These slots provide for the movement of the cutter B back and forth.

At the lower part of the lever C, and extending at right angles with it, is the eccentric, *k*, operating in the slot or oblong collar, *L*, in the part B. An extension of the part *k* forms a bolt, and passes through the handle A, and is held by the nut *i*, shown in fig. 1. This forms the fulcrum.

The mode of operating will be readily seen. By raising or throwing back the lever C, as shown in fig. 2, the jaws or cutters are opened to receive the bolt or rivet. Then, by drawing the lever C towards you, the bolt is cut smoothly, and as close to the nut as you may desire.

What I claim as my invention, and desire to secure by Letters Patent, is—

The tool herein described, when its several parts are constructed and arranged substantially as and for the purposes set forth.

In testimony whereof, I have signed my name to this specification in the presence of two subscribing witnesses.

FRANK MILLER.
